FIG. 4.

UNITED STATES PATENT OFFICE.

GEORGE R. JARMAN, OF BALTIMORE, MARYLAND, ASSIGNOR OF FIFTY ONE-HUNDRED DREDTHS TO WILLIAM A. MATTHEWS, OF BALTIMORE, MARYLAND.

ATTACHMENT FOR FURNACES.

1,115,203.

Specification of Letters Patent. Patented Oct. 27, 1914.

Application filed February 16, 1914. Serial No. 819,006.

To all whom it may concern:

Be it known that I, GEORGE R. JARMAN, a citizen of the United States of America, and resident of Baltimore, in the State of Maryland, have invented certain new and useful Improvements in Attachments for Furnaces, of which the following is a specification.

This invention relates to steam boiler furnaces and the like and relates particularly to smoke consuming attachments for such furnaces and means for creating a draft through the fire bed.

An object of the present invention is to provide novel means for effecting the injection of commingled steam and air into a furnace in such relation to the fire bed as to aid in the combustion of the fuel, the said invention including novel means for heating the air not only through the contact of the steam therewith but by the radiation of steam in a conductor or conduit in such relation to the air supply passage as to effect a raising of the temperature of the air in its passage to the furnace.

A still further object of this invention is to provide novel means for utilizing the steam for drawing air into the conduit leading to the furnace, novel means being furthermore provided for separating moisture from the steam and for removing scale therefrom prior to its passage to the interior of the furnace.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, and in which—

Figure 1 illustrates a view in elevation of a furnace, the wall of which is broken away to illustrate the application of the invention thereto; Fig. 2 illustrates a sectional view of the attachment, the interior part thereof being in elevation; Fig. 3 illustrates an end view showing the outer end of the attachment in elevation; and Fig. 4 illustrates an enlarged sectional view showing the means for supplying steam to the passage leading to the furnace.

In these drawings 5 denotes a furnace

which may be of any appropriate construction but is here shown as having two fuel supply openings controlled by the doors 6 and 7, said furnace having ash pits under the fire beds, the same being controlled by the doors 8 and 9.

In Fig. 1, I have shown different methods of connecting the smoke consumer to the furnace, one example being that illustrated on the left hand side of Fig. 1 where the attachment is applied to the door 8 whereas the method shown on the right hand side of Fig. 1 is to have the attachment projecting through a wall of the furnace in a direction at right angles to that at which the other attachment is applied. The illustration, therefore, will serve to show that the invention is susceptible of use in different positions with relation to the fire bed and the furnace casing as it is in most instances immaterial in what manner the smoke consuming device is applied.

As a means for supplying commingled steam and air to the under surface of the fire bed so that it may pass through the fire bed and support combustion to such an extent as to prevent smoke arising as a part of the products of combustion, the invention comprises an intake pipe 10 preferably contracted or restricted at the inner end as shown at 11, whereas the outer end 12 is flared to form an air intake. The flared end has a face plate 13 provided with apertures 14 and the apertures in the face plate are controlled by a damper 15 which is mounted on the stud 16 so as to rotate in order that the openings 14 may be guarded or unguarded according to the volume of air to be admitted to the pipe. By this means, the operator may acquire the proper mixture of steam and air to support combustion within the furnace and insure favorable results.

A steam supply pipe 17 leads from the steam dome 18 or from any other suitable source of steam supply and within the pipe 10 is a steam conductor 19 shaped to form a coil 20, the said coil extending from the junction of the pipe and its flared portion to a point near the inner end of said pipe, said pipe being then caused to terminate in a straight portion 21 extending through the coil axially of the pipe 10. By reason of the arrangement of parts just indicated, steam is caused to traverse the coil to the

inner end of the pipe 10 and then through the straight portion of the said conductor to a point near the outer end of the pipe 10. The outer end of the conductor is provided 5 with means for permitting the escape of steam so that the jets of steam diverge but flow in a direction generally longitudinally of the pipe 10. In order to accomplish the result intended, the outer end of the conductor 10 for steam has a casing 22 formed of two curved heads provided with flanges 23 and 24 secured together by fastenings such as bolts 25. The inner head has a series of apertures 26 forming jets for the escape of steam, 15 and as stated, the said steam escapes in the general direction of the length of the pipe 10 but has some obliquely disposed travel so that the steam in its passage through the pipe 10 will serve to draw air through the flared end of the pipe which will be mixed 20 with the steam in its travel through the pipe 10, the commingling of the said steam and air being augmented by the presence of the coiled conductor in the pipe. The outer end 25 of the straight portion 21 of the conductor extends through a perforated plate 27 which is secured between the flanges 23 and 24, the said perforated plate 27 serving to arrest scale which may be in the steam and moisture, due to any condensation of the steam in 30 its passage from the boiler to the conductor and said steam and scale may find its escape from the casing through the drain pipe 28.

When the device is used on a door such as 35 the door 8 in Fig. 1, it is moved from the position which it is shown as occupying in Fig. 1, when the door is opened. To facilitate movement of the door with the attachment applied thereto, a flexible conduit 29 extends from the steam pipe 17 to the conductor 19.

From an inspection of the drawing and the foregoing description, it will be apparent that the air heated by the contact of the 45 live steam therewith and by the heat radiating from the conductor within the pipe 10 will so raise the temperature of the air and steam as it emerges from the inner end of the pipe 10 as to serve to support combus-

tion in that heated oxygen is supplied to the 50 fire bed in such quantities or proportions as to insure proper consumption of fuel resulting in a saving in the fuel consumed and protecting the grate bars by reason of the fact that the current of air and steam passes 55 around or between the grate bars in its passage to the fire bed.

I claim—

1. In an attachment for furnaces, a pipe 60 adapted to feed air to a furnace, a steam conductor having a portion thereof coiled within the pipe and an extremity of said conductor extending longitudinally of the pipe within the coiled portion of the conductor, a head on the outer end of the straight portion 65 of the conductor, said head having jets formed therein for the escape of steam, said jets discharging longitudinally of the said pipe.

2. In an attachment for furnaces, a pipe 70 adapted to feed air to a furnace, means for controlling the outer end thereof, a steam conductor having a coiled portion extending longitudinally of the pipe, and a straight portion extending through the coil, said 75 straight portion terminating near the outer end of the pipe, a head on the outer end of the conductor, said head having jets therein, and a perforated plate in the head through which steam passes to the jets. 80

3. In an attachment for furnaces, a pipe adapted to feed air to a furnace, means for controlling the outer end thereof, a steam conductor having a coiled portion extending longitudinally of the pipe, a straight portion 85 extending through the said coil, said straight portion terminating near the outer end of the pipe, a head on the outer end of the conductor, said head having jets therein, a perforated plate in the head through which 90 steam passes to the jets, and a drain pipe in the head.

In testimony whereof, I affix my signature in the presence of two witnesses.

GEORGE R. JARMAN.
